UNITED STATES PATENT OFFICE

PETER THOMSEN, DECEASED, LATE OF CASSEL, GERMANY, BY REINOLD KRUMMacher, ADMINISTRATOR, OF CASSEL, GERMANY, ASSIGNOR TO SCHMIDT'SCHE HEISSDAMPF-GESELLSCHAFT MIT BESCHRÄNKTER HAFTUNG, OF CASSEL-WILHELMSHÖHE, GERMANY, A CORPORATION OF GERMANY

SUPERHEATING SYSTEM FOR FIRE-TUBE BOILERS

Application filed January 22, 1927; Serial No. 162,873, and in Germany January 23, 1926.

This invention relates to a superheating system for fire-tube boilers and has for its object to provide an efficient apparatus whereby the steam may be heated to higher temperatures than have previously been practicable in commercial boilers.

The known type of superheater, wherein the steam is passed through U-loops disposed in the fire tubes of the boiler, is not effective to heat the steam above about 330° C., since the combustion gases, in traversing the fire tubes, transmit too much heat to the boiler water because of the large surface of the fire-tubes in contact with the water. If, on the other hand, a superheater of the so-called furnace flue type is used, in which all the superheater elements are located together in only one large fire tube or chamber or in a few large fire tubes, a higher temperature may be attained. In this case, however, the boiler's evaporating surface in contact with the water becomes too small and the fire gases are not utilized favourably enough.

The present invention is designed to provide means whereby the steam may be superheated to 375 to 400° C. while doing away with these disadvantages. To this end, the superheater comprises two stages, the first stage consisting of a "fire-tube superheater" the pipes of which are disposed in a plurality of fire tubes of the boiler, the second stage consisting of a "furnace flue superheater" the pipes of which are located in one or more comparatively large pipes or tubular chambers, the two stages being connected in series. In the first stage the steam is superheated to a certain degree and in the second stage the steam is raised to the desired high temperature. The second stage is preferably disposed in such a manner with respect to the elements and the header of the first stage superheater, that the pipes of the respective stages may be mounted and taken out without interfering with each other.

While the provision of the second-stage superheater necessarily somewhat reduces the heat-absorbing or evaporating surface of the boiler, yet the second stage of the superheater having a greater and more efficient heating surface as compared with the fire

tube first stage superheater, the whole arrangement is very efficient where it is desired to superheat steam to a high temperature.

The invention is illustrated in the accompanying drawing as applied to a cylindrical marine boiler, but it may be used with other types of boilers.

Fig. 1 is a view of the front end of a marine boiler with parts broken away, showing a preferred embodiment of the invention;

Fig. 2 is a sectional view taken on the line 2—2 of Fig. 1, and

Fig. 3 is a sectional view taken on the line 3—3 of Fig. 1.

The marine boiler 5 shown in the drawing has fire tubes 6 and cylindrical chambers 7 extending the length of the boiler to permit the combustion gases to pass from the rear of the boiler to the smoke box 8 and through the air-preheater tubes 8' to the stack 9.

Steam pipe 10 conducts the steam from the boiler to a wet-steam chamber 11 at the center of the smoke box. Leads 12 extend laterally from chamber 11 to U-loops 13, positioned in the fire tubes 6, and leads 14 conduct the steam from the U-loops back to a second steam chamber 15, the steam attaining a certain degree of superheat during its passage through loops 13 which constitute the first stage of the superheater.

From chamber 15 the steam is conducted by pipes 16 to the headers 17 of the second stage. A number of parallel steam coils 18 extend from headers 17, into the chambers 7 and back to other headers 19, whence the steam is conducted by pipes 20 to the engines. Connecting chambers 21 are interposed between steam coils 18 and headers 17 and 19.

Due to the comparatively large diameter of chambers 7, the gases which come in contact with coils 18 are hotter than those passing through the fire tubes 6; hence the steam in passing through the second stage is raised to a much higher temperature than is reached in the first stage of the superheater.

The fire tube superheater (the primary superheater) of the illustrated embodiment is arranged so that (at least in the lower

100

portion of the boiler) in each horizontal row of fire tubes there are disposed four elements each located in three fire tubes. In the upper portion of the boiler the arrangement is modified so that some of the elements are disposed in two fire tubes only.

10 The second-stage superheater (the secondary superheater) comprises a number of coiled elements arranged in the flues or chambers 7 in parallel planes. In each plane preferably two (as shown in the drawings) or more coils are disposed the ends of which are connected to the connecting chambers 21 removably secured to the headers 17 and 19.

15 The chambers 7 preferably are arranged in the upper portion of the fire tube area of the boiler and on that side of the boiler where the header of the fire tube (first stage) superheater is not situated. Thus in the example 20 illustrated the tubes or chambers 7 are located each on one side of said fire tube area of the boiler whereas the headers 11 and 15 are disposed in front of the middle portion of the boiler. Thus the elements of the different superheaters will not interfere with 25 each other.

What is claimed is:

1. A superheater for a fire tube boiler, comprising besides the fire tubes a tube or chamber of large cross-section extending lengthwise of the boiler and adapted to conduct combustion gases, said superheater comprising a first stage disposed in the fire tubes of the boiler, and a second stage disposed in said 35 tube or chamber and connected in series with said first stage to receive steam therefrom.

2. A superheater for a fire tube boiler, comprising a plurality of elements disposed in the fire tubes of the boiler, headers for said elements, a cylindrical chamber extending 40 through the boiler and adapted to conduct combustion gases, a plurality of elements disposed in said chamber and connected in series with said first mentioned elements to receive steam therefrom, headers for said second mentioned elements, said first mentioned elements being adapted to be mounted and to be taken 45 out without interfering with said second mentioned elements.

3. A superheating system as defined in claim 2, in which the second mentioned elements consist of a series of coils disposed in parallel planes, two or more coils being arranged in each plane, the ends of the coils 55 of each plane being connected to connecting chambers interposed between said coils and the said second mentioned headers.

4. A superheater for a fire tube boiler, comprising a plurality of elements disposed in the 60 fire tubes of the boiler, a header for said elements, an enlarged chamber extending through the boiler and adapted to conduct combustion gases, a plurality of elements disposed in said chamber in parallel planes and 65 connected in series with said first mentioned

elements to receive steam therefrom, and a header for said second mentioned elements, said chamber being arranged on a side of the boiler opposite to said first mentioned header.

5. A superheater for a fire tube boiler, comprising a chamber receiving wet steam from the boiler, a plurality of heat exchange elements arranged to conduct steam from said chamber through the fire tubes, an enlarged chamber extending through the boiler and adapted to conduct combustion gases, heat exchange elements disposed in said chamber and connected in series with said first mentioned elements to receive steam therefrom, said first mentioned heat exchange elements and said second mentioned heat exchange elements being adapted to be mounted and removed independently of each other.
